CAN KEY

Harold A. Davis, Belleville, Mich.

Application January 25, 1946, Serial No. 643,239

7 Claims. (Cl. 220—52)

1

This invention relates to can opening devices, and more particularly to a key device for opening cans.

A main object of the invention is to provide a novel and improved key device for opening cans, said device being very simple in structure, easy to use and being very efficient in operation.

A further object of the invention is to provide an improved key device for opening cans, said device being very economical to manufacture and being adapted to allow the user to readily detach the stripped portion of a can therefrom after the can opening operation whereby the device may be again used.

Further objects and advantages of the invention will appear from the following description and claims, and from the accompanying drawing, wherein:

Figure 1 is a bottom view of a can opening key device according to this invention, shown in operative position with respect to a can at the beginning of the can opening operation.

Figure 2 is a side elevational view of the can opening key device of Figure 1.

Figure 3 is a vertical longitudinal cross-sectional view of the key device of Figure 1.

Figure 4 is a detail transverse cross-sectional view taken through the forward portion of the key device during the can opening operation.

Figure 5 is a detail cross-sectional view taken on line 5—5 of Figure 2.

Referring to the drawing, 11 designates a first body member which is formed of sheet material, such as sheet metal, and comprises a forward jaw element 12 twisted at right angles to the remainder of the body member, a lug element 13 formed intermediate the length of the body member and a lug element 14 formed at the rear end of the body member. Forward jaw element 12 is downwardly bowed in cross-sectional contour to provide a longitudinal trough 29 therein.

Designated at 18 is a second body member formed from sheet material, such as sheet metal, said second body member having a forward jaw element 19 shaped to form a longitudinal generally cylindrical sleeve member 16 which encircles trough-shaped jaw element 12, said sleeve member being formed with a downwardly bowed longitudinal trough portion 30 disposed opposite trough 29. Sleeve member 16 is further formed with a forwardly open-ended longitudinal slot 17, said slot being substantially parallel to trough 30 and adjacent thereto.

Body member 18 is formed with an intermediate lug 20 which is pivotally secured to lug

2

13 by a rivet 22, and is further formed with an end lug 21 disposed adjacent end lug 14. End lug 14 is formed with an arcuate slot 24 through which slidably passes a rivet 25 carried by end lug 21 whereby a limited amount of relative rotation between body member 11 and body member 18 is allowed. A coil spring 26 is secured to body members 11 and 18 in the intermediate recessed portions thereof between lugs 13 and 20 and lugs 14 and 21. Spring 26 biases forward jaw 12 to an open position with respect to trough 30 of sleeve 16. In this position trough member 29 is below the horizontal plane of slot 17.

To use the device the projecting tongue 27 of a can 28 is inserted in slot 17 between the separated trough portions 29 and 30 and body members 11 and 18 are squeezed together against the biasing pressure of spring 26. This moves trough portion 29 toward trough portion 30 thereby crimping tongue 27 to a sinuous shape, as shown in Figure 4. The device is then rotated for about one turn, causing the stripped metal to encircle sleeve 16, as shown in Figure 4. The squeezing pressure on body members 11 and 18 may then be relaxed and the rotation of the device continued until the stripping process is completed. When the stripped metal has been completely removed from the can the metal may be pushed forwardly off sleeve 16, tongue 27 passing through the open end of slot 17. The device is then ready for further use.

It is readily apparent that where a key device as above described is available the necessity of furnishing a key with each can is eliminated.

While a specific embodiment of a key can opening device has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A can opener key device comprising a first body member formed with a first forward jaw portion, a second body member formed with a sleeve encircling said first forward jaw portion, said body members being pivotally connected together, a spring secured between said body members and biasing said first forward jaw portion away from an inner surface of said sleeve, said sleeve being formed with a slot opening at the forward edge of said sleeve and disposed in a plane between the plane of said first jaw por-

45

50

55

tion when it is in its normal position and said inner surface.

2. The structure of claim 1, and wherein said spring is located on the opposite side of the pivotal connection of the body members with respect to said first jaw portion and said sleeve.

3. The structure of claim 1, and wherein said body members are slidably secured together.

4. A can opener key device comprising a first body member formed with a first forward jaw portion, a second body member formed with a second forward jaw portion, said body members being pivotally connected together at their intermediate portions and slidably connected together at their rear portion, the first jaw portion being disposed adjacent said second jaw portion, a spring secured between said body members biasing said jaw portions apart, said spring being

located rearwardly of the pivotal connection between the body members, and a sleeve carried by one of the jaw portions and encircling the other jaw portion, said sleeve being formed with a longitudinal slot opening at the forward edge of the sleeve, said slot being located in a plane between the planes of the jaw portions when said jaw portions are in their normal positions.

5. The structure of claim 4, and wherein each 10 jaw portion lies in a plane at right angles to its body member.

6. The structure of claim 4, and wherein said spring is located between the pivotal connection of the body members and the slideable connection 15 of said body members.

7. The structure of claim 4, and wherein said jaw portions are longitudinally corrugated.

HAROLD A. DAVIS.
